(57) **CLAIM**

The ornamental design for a communications headset, as shown and described.

DESCRIPTION

FIG. 1 is front-bottom-right perspective view of a communications headset showing our new design;

FIG. 2 is a right side view thereof;

FIG. 3 is a left side view thereof;

FIG. 4 is a top view thereof;

FIG. 5 is a bottom view thereof;

FIG. 6 is a front view thereof;

FIG. 7 is a back view thereof;

FIG. 8 is a right side view thereof, with the ear loop in broken lines; and,

FIG. 9 is a left side view thereof with the ear loop in broken lines.

The broken lines showing of the unclaimed environment forms no part of the claimed design.

1 Claim, 3 Drawing Sheets

FIG. 1**FIG. 2****FIG. 3**

FIG. 4**FIG. 5****FIG. 6****FIG. 7**
